UNITED STATES PATENT OFFICE.

JOHN W. RENSHAW AND SAMUEL H. PERIN, OF JEFFERSONVILLE, IND.

MACHINE FOR GRINDING SAD-IRONS.

SPECIFICATION forming part of Letters Patent No. 338,301, dated March 23, 1886.

Application filed June 8, 1885. Serial No. 167,978. (No model.)

To all whom it may concern:

Be it known that we, JOHN W. RENSHAW and SAMUEL H. PERIN, both of Jeffersonville, in the county of Clarke and State of Indiana, 5 and citizens of the United States, have jointly invented certain new and useful Improvements in Machines for Grinding Sad-Irons, of which the following is a specification.

Our invention consists in an improved device for feeding the sad-irons to the grindstone, and in the various combinations of mechanism, hereinafter set forth, and pointed out in the claims.

In the drawings, Figure 1 is a side elevation 15 of the feeding device, the sliding frame upon which the same is mounted, and a portion of the grindstone; Fig. 2, a front elevation of the same; Fig. 3, a reduced view showing one method of imparting lateral motion to the 20 grindstone; Fig. 4, a bottom view of the plate for holding irons; Fig. 5, a side view of the same, and Fig. 6 an end view of the guides for the plates carrying the irons.

A represents a grindstone mounted upon a 25 shaft, *a*, to which revolving motion is imparted by any usual means—as by a belt running upon a pulley, *a'*. A reciprocating motion is also imparted to the shaft by the eccentric *B* and worm-gears *b* and *b'*, or other 30 suitable means. Thus the grindstone has both a revolving and a laterally-reciprocating motion.

C C represent a pair of endless chains carried by sprocket-wheels D D and rollers D' D', 35 mounted upon a suitable frame, E, which is made adjustable with reference to the grindstone by means of any suitable adjusting mechanism.

The chains C are preferably composed of alternate single and double links, and the sprocket-wheels D have forked sprockets adapted to embrace the single links. A series of plates, F, for holding sad-irons, is mounted upon the chains C, each plate preferably extending from 45 chain to chain, and adapted to carry two or more irons.

In the form shown, *f* represents the base of the plate provided with aperture *f'*, adapted to receive the handles of sad-irons, and having a hinged T-arm, *f''*, adjustable with reference to the plate by means of a set-screw, *f'''*.

Attached to the frame E are guides or slides *e*, adapted to receive the plates F as they approach the grindstone and guide them in a fixed path during the contact of the sad-irons with the stone.

We claim as our invention—

1. In a machine for grinding sad-irons, the combination of a grindstone having a rotating and a laterally-reciprocating motion, with one 60 or more endless chains carrying a series of plates for holding sad-irons.

2. In a machine for grinding sad-irons, the combination of a grindstone having a rotating and a laterally-reciprocating motion, with one 65 or more endless chains carrying a series of plates for holding sad-irons, and carried by sprocket-wheels and rollers mounted upon a sliding frame.

3. In a machine for grinding sad-irons, the 70 combination of a grindstone having a rotating and a laterally-reciprocating motion, and one or more endless chains carrying a series of plates for holding sad-irons, and carried by sprocket-wheels and rollers mounted upon a 75 sliding frame, with guides adapted to confine said plates to a straight path during the contact of the irons with the grindstone.

4. In a machine for grinding sad-irons, the combination of a pair of endless chains, of a 80 series of plates for holding sad-irons, each having apertures for receiving the handles of the irons, and a hinged T-arm adjustable by means of a set-screw for clamping the irons in position.

JOHN W. RENSHAW.
SAM'L. H. PERIN.
